TRAFFIC CONTROLLING SYSTEM FOR
RAILROADSOscar S. Field, Rochester, N. Y., assignor to
General Railway Signal Company, Rochester,
N. Y.

Application June 15, 1932, Serial No. 617,264

14 Claims. (Cl. 175—320)

This invention relates to timing apparatus more particularly adaptable for use in traffic controlling systems for railroads.

It is often unsafe to operate a track switch, 5 or a crossover or to clear a signal immediately, without first operating another traffic controlling device and waiting a period of time to allow the operation of such other device to have taken place. For instance, it is unsafe to operate a 10 track switch immediately after placing the signal at stop, for there may be a fast approaching train which cannot stop in response to such signal indication before it reaches the track switch. Under certain conditions, it is not sufficient to 15 have timing apparatus for measuring one particular time period only, but it is desirable not to close a particular contact until different periods of time have elapsed depending on local conditions. In accordance with the present invention, it is proposed to provide a circuit arrangement and associated devices whereby numerous periods of time may be measured by the same apparatus. It is also proposed to use apparatus with few mechanical parts.

25 Other objects, purposes and characteristic features of the present invention will in part be obvious from the accompanying drawing and will in part be more specifically described hereinafter.

30 In describing the invention in detail, reference will be made to the accompanying drawing which shows conventionally one specific embodiment of the present invention.

Referring to the drawing, the relay M may 35 be a signal-at-stop relay, which is only energized when the various signals associated with a track switch are at stop, or this relay M may be controlled in any other way depending upon the manner in which the invention is to be applied, it being for the present assumed that the 40 invention is to be used to delay the operation of a track switch after placing a signal to govern traffic thereover at stop. The switch S may be 45 manually or electrically operated, and is employed to change the timing characteristic of the device, and if opened affords a certain checking function desirable in certain systems. The relays TR¹ and TR² are thermal relays of 50 the type which are compensated against changes in surrounding room temperatures, as well known to those skilled in this art. The adjustable resistances R¹ and R² are used to vary the closing periods of thermal relays TR¹ and TR² 55 the adjustment of these resistances having prac-

tically no effect on the opening periods of these relays.

The stick relays SR¹ and SR² perform the usual hold-over function characteristic of relays of this kind. 60

Operation

Let us first assume that the switch S is open, and let us observe how the closure of contact 1 of the relay M will result in connecting the terminal (+) of a suitable battery to the various terminating wires after the lapse of various intervals of time. Closure of the contact 1 of the relay M will first result in energization of the heating coil 2 of the relay TR¹, by closure of the 70 following circuit:— beginning at the terminal (+) of said battery, front contact 1 of the relay M, wires 3 and 4, adjustable resistance R¹, heating coil 2, wire 5, back contact 6 of the stick relay SR¹ and to the other terminal (—) of said 75 battery. The closure of this circuit results in heating of the coil 2, thereby causing the thermal relay to be gradually moved to its heated dotted position, in which position the following pick-up circuit for the relay SR¹ is closed:— 80 beginning at the terminal (+), front contact 1 of relay M, wires 3 and 4, front contact 10 of the thermal relay TR¹, wires 11 and 12, winding of the relay SR¹ to the other terminal (—). With the relay SR¹ picked up, it will be stuck 85 up through the following stick circuit:—beginning at the terminal (+), front contact 1 of the relay M, wires 3 and 4, resistance R¹, heating coil 2, wire 5, stick contact 6 of the relay SR¹, wires 13 and 12, winding of the relay SR¹ to the 90 other terminal (—).

95 It will be noted that the circuit just traced includes the heating coil 2 in series with the winding of the stick relay SR¹. Since the resistance of the relay SR¹ is fairly high, the current will be reduced to a very low value, so that the thermal relay TR¹ will be permitted to cool and eventually again close its back contact 10.

When this occurs, the following energizing 100 circuit for the heating coil 22 of the thermal relay TR² is closed:— beginning at the terminal (+), front contact 1 of the relay M, wires 3 and 4, back contact 10 of the stick relay TR¹, wires 14 and 15, front contact 16 of the relay SR¹, wires 17 and 18, adjustable resistance R², heating coil 22 of the relay TR², wire 23, back contact 24 of the relay SR² to the other terminal (—) of said battery. 105

After another interval of time, the thermal relay TR² will be heated to a temperature to 110

close its front contact 25 resulting in the closure of a pick-up circuit for the relay SR²:— beginning at the terminal (+) of said battery, front contact 1 of the relay M, wires 3 and 4, back contact 10 of the thermal relay TR¹, wires 14 and 15, front contact 16 of the relay SR¹, wires 17 and 18, front contact 25 of the relay TR², wires 27 and 28, winding of the relay SR² to the other terminal (—). The relay SR² will 10 of course be picked up thereby closing the following stick circuit:— beginning at the terminal (+), front contact 1 of the relay M, wires 3 and 4, back contact 10, wires 14 and 15, front contact 16 of the relay SR¹, wires 17 and 18, resistance unit R², heating coil 22, wire 23, stick contact 24 of the relay SR², wires 29 and 28, winding of the relay SR² to the other terminal (—).

It will be noted that by the completion of the 20 stick circuit for the relay SR² the resistance of the relay SR² has been included in series with the heating coil 22 of the relay SR² as a result of which the current is reduced to a low value allowing cooling of the thermal relay TR² and 25 re-closure of its back contact 26 after the lapse of another increment of time. When this occurs current may flow to the terminating wire 30 through the following circuit:— beginning at the terminal (+), front contact 31 of the relay SR², wires 32 and 33, back contact 26 of the thermal 30 relay TR² to the wire 30.

If we now assume that fifteen seconds are required to heat the coils of the thermal relays TR¹ and TR² to a temperature to close their 35 front contacts, and if we further assume that it requires one and one-half minutes for the thermal relay TR¹ to again cool to a temperature where its back contact is closed and with the energizing current for the stick relay SR¹ flowing 40 through its heating coil, and that it requires two and one-half minutes for the thermal relay TR² to cool to a temperature to reclose its back contact and with energizing circuit for the stick relay SR² flowing through its heating 45 coil, various periods of time will elapse between the closure of the contact 1 of the coil M and the instant that the terminal (+) of the battery is connected to the wires 30, 40 or 50, respectively.

50 It is readily apparent that the terminal (+) is connected to the wire 50 after the lapse of two periods of time, namely, the time necessary to heat the thermal relay TR¹ and the time required for this relay TR¹ to cool, so that the total period 55 of time following the closure of contact 1 is fifteen seconds plus one and one-half minutes or a total of one and three-fourth minutes before the terminal (+) is connected to the wire 50. It is readily apparent that the contact 31 of 60 relay SR² closes fifteen seconds later, namely, the time required for the thermal relay TR² to be heated, so that the terminal (+) is connected to the wire 40 fifteen seconds later, or after the lapse of two minutes following the closure of 65 contact 1. Also, it is readily apparent, since it has been assumed that two and one-half minutes are required for the thermal relay TR² to cool, that current may flow from the terminal (+) through contacts 31 and 26 of relay SR² and TR², respectively, to the wire 30 after the lapse 70 of an additional period of two and one-half minutes making a total of four and one-half minutes, as indicated in the table on the drawing.

75 It is thus seen that, with the time characteris-

tics of the thermal relays TR¹ and TR² as arbitrarily selected above, time periods of one and three-fourth minutes, two minutes and four and one-half minutes may be measured with the contact S open. If now the contact S is closed, no cooling of the thermal relay TR¹ will be required to pass the current from the terminal (+) through the front contacts 1 and 16 of the relays M and SR¹, so that the time periods here-tofore mentioned will be reduced by one and one-half minutes, thus resulting in time period lapses of three minutes, one-half minute and one-fourth minute with the switch S closed. It is, of course, understood that the relays used may have any suitable timing characteristics.

Having thus shown and described one specific embodiment of the invention, it is desired to be understood that the particular embodiment of the invention illustrated has not been selected for the purpose of showing the scope of the invention nor its precise construction, and that various changes and modifications may be made to adapt the invention to the particular problem encountered in practicing the same all without departing from the spirit or scope thereof, except as demanded by the scope of the following claims.

What I claim as new is:—

1. In combination in a railway signal system, a thermal relay, a stick relay, an energizing circuit for said thermal relay including a back contact of said stick relay, a pick-up circuit for said stick relay including a front contact of said thermal relay, a control circuit including a front contact of said stick relay and a back contact of said thermal relay, and a separate contact for at times shunting said back contact of said thermal relay, whereby said control circuit may be closed upon heating and cooling of said thermal relay when said separate contact is open but may be closed upon heating alone of said thermal relay when said separate contact is closed.

2. In combination in a railway signal system, a thermal relay, a stick relay, an energizing circuit for said thermal relay including a back contact of said stick relay, a pick-up circuit for said stick relay including a front contact of said thermal relay, a control circuit including a front contact of said stick relay and a back contact of said thermal relay, and manually operable means for at times shunting said back contact of said thermal relay in said control circuit.

3. In combination, two thermal relays, a stick relay for each thermal relay, a pick-up circuit for each stick relay closed upon heating of its associated thermal relay, an energizing circuit for each thermal relay including a back contact of its associated stick relay, and a control circuit dependent upon front contacts of said stick relays and back contacts of said thermal relays.

4. In combination, two thermal relays, a stick relay for each thermal relay, a pick-up circuit for each stick relay closed upon heating of its associated thermal relay, an energizing circuit for each thermal relay including a back contact of its associated stick relay, a front contact of one of said stick relays included in the energizing circuit of the other of said thermal relays, and a control circuit including a front contact of the stick relay associated with said other thermal relay.

5. In combination, two thermal relays, a stick relay for each thermal relay, a pick-up circuit for each stick relay closed upon heating of its associated thermal relay, an energizing circuit

- for each thermal relay including a back contact of its associated stick relay, a front contact of one of said stick relays included in the energizing circuit of the other of said thermal relays, 5 and a control circuit including a front contact of the stick relay associated with said other thermal relay and also including a back contact of said other thermal relay.
6. In combination, a first thermal relay, a first stick relay having a back contact included in the energizing circuit of said first thermal relay and having a pick-up circuit including a front contact of said first thermal relay, a second stick relay, a second thermal relay having an energizing 10 circuit including a back contact of said second stick relay and a front contact of said first stick relay, and a control circuit including a front contact of said second stick relay.
7. In combination, a first thermal relay, a first stick relay having a back contact included in the energizing circuit of said first thermal relay and having a pick-up circuit including a front contact of said first thermal relay, a second stick relay, a second thermal relay having an energizing 15 circuit including a back contact of said second stick relay a front contact of said first thermal relay and back contact of said first thermal relay, and a control circuit including a front contact of said second stick relay.
8. In combination, a first thermal relay, a first stick relay having a back contact included in the energizing circuit of said first thermal relay and having a pick-up circuit including a front contact of said first thermal relay, a second stick relay, a second thermal relay having an energizing 20 circuit including a back contact of said second stick relay and a front contact of said first stick relay, and a control circuit including a front contact of said second stick relay.
9. In combination, a first thermal relay, a first stick relay having a back contact included in the energizing circuit of said first thermal relay and having a pick-up circuit including a front contact of said first thermal relay, a second stick relay, a second thermal relay having an energizing 25 circuit including a back contact of said second stick relay and a front contact of said first stick relay, and a control circuit including a front contact of said second stick relay.
10. In combination, a first thermal relay, a first stick relay having a back contact included in the energizing circuit of said first thermal relay and having a pick-up circuit including a front contact of said first thermal relay, a second stick relay, a second thermal relay having an energizing 30 circuit including a back contact of said second stick relay and a front contact of said first stick relay and a back contact of said second thermal relay.
11. In combination, a first thermal relay, a first stick relay having a back contact included in the energizing circuit of said first thermal relay and having a pick-up circuit including a front contact of said first thermal relay, a second stick relay, a second thermal relay having an energizing 35 circuit including a back contact of said second stick relay and a front contact of said first thermal relay, a control circuit including a front contact of said second stick relay and a back contact of said second thermal relay.
12. In combination, a plurality of circuits to be controlled, a control contact, a plurality of thermal devices, governing means for causing each of said devices to be heated and cooled in sequence upon the closure of said control contact, and means including said devices and said governing means for rendering said circuits successively responsive to control by said control contact.
13. In combination; a plurality of circuits to be controlled; a control contact; a plurality of thermal relays, one for each of said circuits; governing means for causing said thermal relays to be respectively heated and cooled in sequence upon the closure of said control contact; and means for closing that particular one of said circuits associated with a particular thermal relay upon the completion of its heating and cooling operation, whereby said circuits are closed sequentially and predetermined times respectively after the closure of said control contact.
14. In combination; a plurality of circuits to be controlled; a control contact; a plurality of thermal relays, one for each of said circuits; governing means for causing said thermal relays to be respectively heated and cooled in sequence upon the closure of said control contact; means for closing that particular one of said circuits associated with a particular thermal relay upon the completion of its heating and cooling operation; and other means for at times governing said first mentioned means so that the cooling time of the first of said plurality of thermal relays is ineffective; whereby said circuits are closed sequentially with certain predetermined times respectively after the closure of said control contact if said other means is effective.

OSCAR S. FIELD.
